GRILLE

John A. Germonprez, Grosse Pointe Park, Mich.,
assignor to Barber-Colman Company, Rock-
ford, Ill., a corporation of Illinois

Continuation of application Serial No. 757,494,
December 14, 1934. This application June 26,
1936, Serial No. 87,387. In Canada May 28,
1936

14 Claims. (Cl. 98—114)

The invention pertains to grilles of the type employed in air conditioning systems for the purpose of covering the discharge ends of air ducts through which air is discharged under pressure into rooms or other spaces to be conditioned. In order to effect proper distribution of the air without creating uncomfortable drafts, particularly in cooling systems, it is necessary to control the air in its discharge. On the other hand, conditions encountered in practice vary so widely, for example, in the size of the room, the location or disposition of the ducts, and the temperature and velocity of the air discharged, as to require a large variety of different grille structures.

One object of my invention is to provide a novel and advantageous construction for grilles of the character indicated such that they may be adapted readily to meet widely different requirements in use without, however, adding appreciably to the cost of construction and while maintaining a substantially uniform appearance.

Another object is to provide a grille structure of the type composed of a multiplicity of thin fins supported in spaced parallel relation edge-wise to the flow of air into a room or other space, in which the incoming air is advantageously controlled through the cooperative action of groups of deflectors formed on the discharge edge portions of the fins.

A further object of the invention is to provide a grille having groups of deflectors cooperating in a novel manner to increase the range of travel of the air after its discharge and to avoid any unpleasant blast of air upon the room occupants.

Still another object is to provide a grille having a plurality of groups of deflectors adapted for effectual cooperation to produce a shorter range of travel, together with improved distribution and intermixture with the room air.

In the accompanying drawings:

Figure 1 is a fragmentary vertical sectional view illustrating schematically the action upon the moving body of air in a grille constructed and arranged for a long range of air travel.

Fig. 2 is a fragmentary front elevational view of a grille of the character shown somewhat schematically in Fig. 1.

Fig. 3 is an enlarged sectional view taken substantially in the plane of line 3—3 of Fig. 2.

Fig. 4 is a similar view taken in the plane of line 4—4 of Fig. 2.

Figs. 5, 6 and 7 are perspective views showing details of construction.

Fig. 8 is a partially schematic view similar to

Fig. 1 but illustrating the arrangement employed for a grille designed for a shorter air travel.

Fig. 9 is a fragmentary front elevational view of a grille of the type illustrated schematically in Fig. 8.

Fig. 10 is a fragmentary view showing in plan the spreading action effected by the central portion of the grille shown in Fig. 8.

Fig. 11 is an enlarged fragmentary sectional view taken in the plane of line 11—11 of Fig. 9.

Fig. 12 is an enlarged perspective view illustrating the construction of certain of the fins employed in the central section of the grille shown in Fig. 9.

In carrying out my invention, I employ in the construction of each grille a series of thin narrow strips or fins mounted within a suitable supporting frame. The fins are arranged with opposing side surfaces uniformly spaced a short distance apart so as to define narrow air passages through the grille having opposed walls constituting guiding surfaces acting upon the air streams to guide the same in their passage through the grille. The entering air is controlled, according to the conditions encountered, by the provision along the fins of inclined deflecting elements preferably in the form of projections or protrusions and formed along the discharge edge portions of the fins and constructed in novel ways and arranged in groups so as to produce different deflecting effects.

While the aforesaid protrusions or projections serve primarily as deflecting elements, in the case of certain of the groups, the degree of deflection imparted thereby to the respective air streams may be relatively small. Such elements, however, may, because of their size, shape and spacing relative to each other, serve to perform a diffusing function and cooperate with other groups of elements to produce desirable results under the varying conditions encountered in practice.

Referring now to Figs. 1 and 2, the grille structure here shown comprises a rectangular frame 13 of suitable construction adapted to be positioned across the open end of an air duct *a* discharging into a room near the ceiling *b* thereof. Mounted within the frame 13 are a series of thin parallel fins 14 preferably constructed of thin narrow strips of sheet metal having their opposing side faces disposed parallel and spaced a short distance apart so as to define a plurality of narrow transversely elongated air passages. The fins 14 are of substantially greater depth in a front to rear direction than the spacing between

them so that their opposing side faces constitute air directing and guiding surfaces. Thus the fins serve to divide the moving body of air into separately confined streams.

5 At spaced points throughout the length of the fins they are preferably supported so as to maintain uniform the spacing between them. Any preferred construction may be employed for this purpose. That herein shown is of the same character disclosed and claimed in my copending application Serial No. 712,550, filed February 23, 1934, now Patent No. 2,140,993, dated December 20, 1938. It comprises a series of spacing elements formed by folds 15 (Figs. 5 and 6) with 10 apertures 16 formed centrally through the folds and substantially midway between the opposite edges of the fins to receive supporting bars 17.

The grille illustrated in Fig. 2 is adapted for use where a long range of air travel, for example, 20 fifty or more feet, is desired, and particularly when the air to be delivered into the room or other space is at a temperature substantially below room temperature. It has been found that when a moving body of cold air is delivered at 25 high velocity, say 1000 feet per minute, through a grille having plain straight fins arranged horizontally and edgewise to the flow of air, the range of outward travel of the air is not of sufficient length for proper distribution in the case of a 30 long room. This is apparently for the reason that upon leaving such a grille the moving body of air expands transversely both in a vertical and horizontal direction, resulting in a substantial enlargement of its cross sectional area and perimeter a short time after the air leaves the 35 grille. Accordingly the resistance interposed by the room air to the travel of the incoming air is increased considerably, and such increase in resistance, coupled with the effect of gravity on the heavier cool air causes the latter to descend into 40 the occupancy level of the room in the form of a strong and cold blast, which is very uncomfortable.

In an attempt to avoid this disadvantage, it is 45 sometimes the practice to incline the fins upwardly and outwardly so as to direct the air toward the ceiling. This arrangement has not proven satisfactory apparently because a slight upward deflection has little effect, and in the 50 case of a sharp upward deflection the body of air strikes the ceiling and is deflected downwardly into the center of the room in the form of a cold blast. Increasing the velocity of the incoming air to increase the range of travel is objectionable on account of the noise produced and furthermore does not have the desired effect because of the expansion and gravitational descent 55 of the cool air above referred to.

To overcome the defects of prior structures 60 and increase the range of travel of air, I produce a vertical convergence of the air portions of air streams issuing from the upper and lower portions of the grille, thereby effecting a concentration of the air into a narrow body traveling at a 65 relatively high velocity and expanding or spreading gradually for intermixture with the room air. This is accomplished through the provision of deflectors at the discharge edges of the fins, preferably in the form of a multiplicity of protrusions 70 or projections formed by bending the fins at longitudinally spaced intervals, and arranged in a plurality of groups having different deflecting effects, the fins in at least the upper and lower portions of the grille being disposed horizontally. 75 In the preferred embodiment of the invention the

fins are arranged in groups or sections corresponding to the grouping of the deflecting elements so that all of the deflecting elements on any given fin are uniform in character. Thus the grille is divided, in the present instance, into 5 three sets or sections of fins, one for each group, and consisting of a central section 14^a, a lower section 14^b, and an upper section 14^c; and the projections of the several groups are so constructed and proportioned as to provide different 10 effective deflecting effects such that the moving body of air passing through the grille is divided into a central stream with a slight upward deflection, and upper and lower streams respectively deflected downwardly and upwardly. 15

By the arrangement set forth, all of the deflecting elements of each fin are uniform in character, thereby simplifying manufacture. Thus the fins of the intermediate section 14^a are provided along their discharge edge portions with 20 relatively small somewhat rounded protrusions 18 projecting upwardly and outwardly across the narrow passage formed between adjacent fins. The elements 18 are so proportioned and spaced relative to each other as to produce a light deflection of the individual air streams, thereby imparting a small upward deflection to the portion of air passing through the central or intermediate section 14^a.

The fins of the upper and lower sections 14^b 30 and 14^c are formed with flat relatively longer deflecting elements 19 of substantially greater area and therefore of greater deflecting effect than the rounded elements 18. Also, these upper and lower elements 19 have relatively different 35 deflecting effects in that they are oppositely disposed, those of the upper group projecting from the under sides of the fins and being inclined outwardly and downwardly toward the face of the grille while those of the lower group are 40 oppositely inclined outwardly and upwardly and project from the upper sides of their fins. Thus the deflecting elements 19 act on the air streams flowing through the fins of the upper and lower groups 14^b and 14^c to direct the streams downwardly and upwardly respectively at opposite angles to a perpendicular to the face of the grille while the elements 18, being of smaller effective area, direct the air stream through the central section 14^a upwardly and at a smaller angle to 45 said perpendicular.

Due to the opposite inclination of the deflecting elements of the central and upper sections of the grille, the upper fin of the central section (Fig. 7) omits the folds 15, being merely provided with slots 16^a for the passage of the supporting bars 17. 55

Assuming that the grille is used as above indicated for controlling the discharge of cold air into a large room or other space, the air in its 60 passage through the grille, is acted upon by the opposed guiding surfaces of the horizontal fins so as to be sustained against a too rapid descent due to the greater effect of gravity on the heavy cold air. By arranging the deflecting elements 65 so as to produce a somewhat greater upward deflection of that portion of the air issuing from the lower portion of the grille, the guiding effect of the fins in sustaining the air is augmented. At the same time the downward deflection produced by the deflecting elements acting upon the air passing through the upper portion of the grill, prevents the body of air from being deflected upwardly against the ceiling and thus prematurely deflected downwardly into the room. 75

An important feature is the convergence of the air streams issuing from the upper and lower portions of the grille. This effects a concentration of the air into a narrow body of relatively high velocity and thus retards the natural expansion of the air, reducing the resistance interposed by the room air. As a result, the entering air expands gradually and remains suspended above the occupancy level for a longer time, during which the heat of the surrounding air is transmitted by conduction to and, to some extent, intermixture with the entering air. Accordingly, by the time the incoming air descends into the occupancy level of the room, its temperature and velocity is such as not to be objectionable.

While I have herein shown in Fig. 2 the upper and lower sections of the grille as composed of the same number of fins and a somewhat larger number of fins in the central section, it will be apparent that the number of fins in each section may be varied relative to the number in other sections. Also, it is to be understood that my invention is not limited to the particular number of sections shown. Where, however, a maximum range of air travel is desired, an arrangement by which a greater upward than downward deflection is obtained, has been found most effective.

Where the desired length of travel of the air from the grille is relatively short, as for example twenty feet, it has been found advantageous to employ a vertical arrangement of the fins, with the deflecting elements arranged in a plurality of groups lengthwise of the grille and so constructed that instead of a convergence of the air streams in a vertical plane, as in the case of Figs. 1 and 2, the natural expanding tendency is augmented by producing a divergence of air streams horizontally, while at the same time effecting rapid intermixture with the warm air. In Figs. 8 and 9, I have shown a grille having a main section 14^a of this character. It comprises in the present instance a plurality of vertical fins 20 mounted in horizontally spaced relation in a manner generally similar to that of the horizontal fins above described in the case of the grilles shown in Fig. 2. Thus these vertical fins are formed of thin strips of sheet metal with deflecting elements at their discharge edges arranged in a plurality of groups and operative to effect a gradual spreading action on the moving body of air (Fig. 10).

In the present instance, six groups are shown, including two central groups having small rounded deflecting elements 18' with the elements of these two groups projecting in opposite directions from a vertical median line. Adjacent these two central groups in opposite directions are third and fourth groups having flat elongated deflecting elements 19'; and adjacent these latter groups in turn are two end groups having deflecting elements 21 of still greater deflecting effect. The latter elements are herein shown as rounded but of substantial length and of somewhat greater inclination than the deflecting element 19' of the adjacent groups.

With this arrangement, a moving body of air passing through the main section of the grille is deflected laterally from the central median line to a gradually increasing extent toward the opposite ends of the grille, as shown in Fig. 10. That portion of the air passing through the central group is acted upon by the elements 18' to impart only a slight degree of deflection. At the same time, because of the shape and spacing of

these elements, a turbulence is imparted to the air beyond the grille so that this portion of the air stream mixes more rapidly with the room air. The other elements 19' and 21, while producing a similar turbulence, serve more particularly to effect a lateral distribution of the body of air over a wider area. Because of the rapid mixture of the entering air with the room air, an undesirable blast of cold air upon the room occupants is avoided.

In addition to the main section above described, the grille may, as shown in Fig. 9, also include upper and lower sections 14^c and 14^b, similar to the upper and lower sections of the grille shown in Fig. 2, so that the upper and lower streams converge upon the central stream. The latter is acted upon by the deflectors to effect a lateral spreading of this portion of the air over a wider area while the upper and lower converging streams serve to increase the range of travel. Thus this arrangement is advantageous in the case of a room which is long and wide. As herein shown, a smaller number of fins is employed in each of the upper and lower sections. When this construction is employed, the fins of the main or central section may be suitably supported at their upper and lower ends in frame members 22 and 23, and also may, if desired, be supported between their ends by means of a longitudinal bar 24 extending through apertures in the fins 30 in the manner described above in connection with the grilles shown in Fig. 2.

It will be seen that through the provision of fins having deflecting elements arranged in a plurality of groups with the elements of adjacent groups of different deflecting effects, it is possible to control effectually a moving body of air discharged at high velocity, so as to meet the varying conditions encountered in practice.

Of primary importance in the construction of my improved grille is the mounting of the fins in parallel relation, coupled with the arrangement of inclined deflecting surfaces in different groups to accomplish the desired control of the air to meet the various conditions encountered in use. The parallel construction and arrangement is advantageous owing to the fact that all of the fins may be uniformly mounted in the supporting frame so that the manufacturing operation is greatly simplified. This is particularly important where all the deflecting surfaces on each fin are uniform in character, since all that is required in manufacture is the assembly of different types of fins in different groups as may be desired.

A further important advantage flowing from the use of groups of deflecting elements of different deflecting effects, with all of the fins in parallel relation, is that the discharge edge portions are uniformly spaced so that the front face of the grille presents a more uniform appearance than would be possible by positioning the fins at different angles. Also, the elements serve to break up the straight lines formed by the front edges of the fins, so that the transition point between fins having different deflecting elements is rendered less noticeable.

In the appended claims the expression "different effective deflecting capacities" is intended to include difference in the direction as well as extent of deflection.

This application is a continuation of my pending application Serial No. 757,494, filed December 14, 1934.

I claim as my invention:

1. A forced air grille adapted to cover an air discharge opening and comprising a multiplicity of thin substantially flat fins supported horizontally one above the other with opposite side faces in closely spaced parallel relation across said opening, said fins being divided into a plurality of sections including an upper section and a lower section, and inclined deflecting elements spaced along the discharge edge portions of the fins of said upper and lower sections with the elements of said upper and lower sections inclined toward each other whereby to converge the portions of the air current discharged through the fins of said upper and lower sections.
2. In an air conditioning system, the combination with a duct from which air is discharged, of a grille covering the open end of said duct and comprising a plurality of thin horizontally disposed fins having opposing side faces in vertically spaced parallel relation across said opening, said fins being divided into three sets including a central set and two outer sets above and below the central set, and deflecting elements formed along the discharge edge portions of the fins of the outer sets and inclined toward each other whereby to converge the side portions of the air current toward the streams discharged through the fins of the central set.
3. A forced air grille comprising, in combination, a series of thin horizontally disposed fins having opposed parallel side faces uniformly spaced a short distance apart vertically so as to form narrow air passages, and a multiplicity of inclined deflecting elements formed on the discharge edge portions of the fins and including upper downwardly inclined elements and lower upwardly inclined elements, said deflecting elements cooperating to effect a convergence of the air flowing from the upper and lower portions of the grille, and the combined deflecting capacities of the upwardly acting elements being greater than the combined capacities of the downwardly acting elements.
4. In an air conditioning system, the combination with a duct from which air is discharged, of a grille covering the open end of said duct and comprising a plurality of thin substantially flat vertical fins supported in uniformly spaced parallel relation, said fins being divided into a central section and terminal sections arranged side by side, the fins of said terminal sections having inclined deflecting surfaces acting on the air streams flowing between adjacent fins to cause divergence of the streams relative to the streams between the fins of said central section, and the fins of said central section having protrusions spaced a substantial distance apart and arranged to be impinged upon by the central air streams.
5. A grille for covering the open end of an air duct in an air conditioning system, comprising a plurality of thin vertical fins with opposing side faces disposed in closely and equally spaced parallel relation across said open end, said fins being divided into a central section, intermediate sections on either side thereof, and a terminal section adjacent each intermediate section, the fins of said intermediate and terminal sections having deflecting elements facing away from said central section whereby to cause divergence of the air streams discharged from the grille, and the elements on said terminal sections having larger deflecting areas than those on the intermediate sections.
6. A grille for controlling the discharge of air under pressure from an air duct or the like comprising, in combination, a central fin section having a plurality of thin narrow strips supported vertically with opposing side surfaces in laterally spaced relation and defining a multiplicity of narrow air passages of greater depth in a front to rear direction than the spacing between said surfaces, said strips having a multiplicity of deflecting elements formed out of the strips and inclined outwardly for impingement by the air streams flowing through said passages, said deflecting elements being arranged in a plurality of groups horizontally of the grille and cooperating to effect a lateral divergence of the air passing through said central section, and upper and lower fin sections having horizontally disposed strips with oppositely inclined deflecting surfaces adapted to converge the upper and lower portions of the air toward the central portion issuing from said central section.
7. A forced air grille adapted to cover an air discharge opening and comprising a plurality of thin fins supported with opposing side faces in parallel relation, said fins being divided into three sets including a central set and two outer sets, and deflecting elements formed along the discharge edge portions of the fins of the outer sets and inclined toward each other whereby to converge the side portions of the air currents toward the streams discharged through the fins of the central set.
8. A grille for controlling the discharge of air horizontally into a room, having two different sections disposed one above the other and each comprising a series of fins disposed in edgewise relation to the general direction of air flowing through the grille, the fins of the upper section being constructed and arranged for the discharge of air substantially horizontally into the room and the fins of the lower section extending horizontally in closely spaced relation and providing deflecting surfaces impinged upon by that portion of the body of air passing through the lower section and disposed so as to direct such portion bodily upward and at an angle relative to the direction of flow of the portion of the body of air passing through the upper section of the grille, whereby said lower portion of the air body exerts a lifting force on the upper portion of said body to increase the range of travel of the air outwardly from the grille.
9. A register or grille for covering the discharge opening of an air duct comprising a frame a series of parallel fins supported by said frame in edgewise relation to the direction of the flow of air forced out of said duct and being of sufficient width relative to their lateral spacing as to impart positive directional control to the air flow through the grille, said fins having longitudinally spaced portions of their discharge edges inclined relative to the plane of the fins to provide diffusing and deflecting elements, and said fins being arranged in laterally spaced groups with the deflecting elements of the different groups having different effective deflecting areas whereby to effect a greater deflection of the air discharged through one group of fins than that discharged through the adjacent group.
10. A grille through which air is adapted to be blown comprising a frame, a series of fins disposed in closely spaced parallel relation and mounted in said frame in edgewise relation to the general direction of the air flow through the grille, said fins being disposed in horizontal position and closely spaced so as to impart directional control to the air flow therethrough, two

sets of closely spaced horizontal fins respectively disposed above and below said first mentioned fins and having deflecting surfaces inclined toward said first mentioned fins whereby to deflect converging air streams toward the stream defined by said first mentioned fins.

11. A grille through which air may be blown comprising a frame, a series of fins mounted horizontally in the frame and extending transversely to the plane of the frame, the fins at the top and bottom of the grille being provided with angular flanges adapted to deflect converging streams of air toward the center of the grille, the grille being arranged to allow a stream of air to flow through the center thereof between the converging air streams.

12. A grille comprising a frame, a series of spaced parallel fins supported by said frame in edgewise relation to the direction of the flow of air through the frame and being of sufficient width relative to their lateral spacing as to impart directional control to the air flow, said fins having longitudinally spaced portions of their discharge edges inclined relative to the plane of the fins to provide diffusing and deflecting elements, and said fins being arranged in laterally spaced groups with the deflecting elements of the different groups projecting in opposite directions and acting to incline the air streams discharged through the different groups in opposite directions relative to a perpendicular to the grille face.

13. A grille comprising a frame, a series of fins supported in spaced parallel relation by said frame edgewise to the direction of the in-flow through the frame, said fins being arranged in laterally spaced groups and having longitudinally spaced portions of their discharge edges inclined relative to the plane of the fins to provide diffusing and deflecting elements, the deflecting elements of different groups projecting from their fins in different directions and being differently shaped so as to provide different effective deflecting effects whereby to incline the air streams discharged through the different groups in opposite directions and at different angles relative to a perpendicular to the grille face.

14. A grille comprising a frame, a series of spaced parallel fins supported by said frame in edgewise relation to the direction of the flow of air through the frame and being of sufficient width relative to their lateral spacing as to impart directional control to the air flow, said fins having longitudinally spaced portions of their discharge edges inclined relative to the plane of the fins to provide diffusing and deflecting elements, and said fins being arranged in laterally spaced groups with the deflecting elements of the different groups differently shaped and acting to produce correspondingly different degrees of deflection of the air streams discharged through the different groups.

JOHN A. GERMONPREZ.
